UNITED STATES PATENT OFFICE.

HENNING TEODOR TORNBERG, OF FLUSHING, NEW YORK, ASSIGNOR TO AKTIEBOLAGET
SVENSKA KULLAGERFABRIKEN, OF GOTEBORG, SWEDEN, A CORPORATION OF
KINGDOM OF SWEDEN.

MEANS FOR TESTING THE PROGRESS OF WORK IN MACHINES FOR GRINDING BODIES
OF REVOLUTION.

Application filed April 18, 1921. Serial No. 462,377.

To all whom it may concern:

Be it known that I, HENNING TEODOR TORNBERG, a subject of the King of Sweden, residing at Flushing, Long Island, New York, have invented certain new and useful Improved Means for Testing the Progress of Work in Machines for Grinding Bodies of Revolution, of which the following is a specification, reference being had to the drawing accompanying and forming a part thereof.

In machines of the type for grinding bodies whereof the surface or surfaces to be ground are figures of revolution, such as those of rollers for roller bearings, the progress of the grinding operation has usually been tested by the workman stopping the machine from time to time and ascertaining, with the aid of a caliper-gauge, whether or not the desired diameter of the body has been attained. This method of testing is, obviously, time-wasting especially in the later stages when the grinding operation nears completion.

In order to facilitate the testing of the progress of grinding, the grinding machine is provided, according to the present invention, with a caliper-gauge, or the like, arranged concentrically with a rotary working spindle of the machine, said gauge being preferably adapted to rotate at the same speed as that of the working spindle, and to be moved, in order to test or gauge the diameter of the body, into or towards the testing or gauging position, during a return movement of the reciprocating grinding disc away from the gauge. The gauging can thus be performed without stopping the machine, and by rotating the gauge with the working spindle, i. e., with the body undergoing grinding, a further advantage is gained in that the wear of the gauge as it is moved along the body will be a minimum.

In the accompanying drawings, Fig. 1 is a longitudinal section of a working spindle of a grinding machine provided with a gage in accordance with the invention.

Fig. 2 is an elevation partly in section of a portion of a grinding machine embodying my invention, showing the means for moving the caliper gage and for operating a cut-off or declutching device, the grinding

wheel being shown acting on the work and the gage retracted.

Fig. 3 is a similar view showing the grinding wheel free of the work and the caliper gage advanced in engaging relation with the same.

In the drawing, referring particularly to Fig. 1, 1 designates the rotary working spindle, and 2 designates the body to be ground, which is shown as a roller with a convex rolling surface. This roller is secured, in known manner, for instance by a pin A, Figs. 2 and 3, to the spindle 1, so as to rotate therewith. Placed on the spindle 1 is a sleeve 3 rotating with the spindle but adapted to be moved axially relatively thereto, the connection for permitting this being for instance a pin 4 attached to the spindle and located in a slot 5 in the sleeve 3 extending parallel to the axis of the sleeve.

The sleeve 3 at one end carries a caliper-gauge consisting, for instance, of a fixed shoulder arm or abutment 6 and a diametrically opposed shoulder arm or abutment 7 seated in a radial slot in the ring 8 and adjustable in said slot relatively to the part 6. The adjustment of the abutment 7 is effected by means of an adjusting screw 7^a threaded in the ring 8, with the head of the screw in position to engage the outer edge of the abutment, which latter is held in its adjusted position by means of a binding screw 7^b threaded in the outer end of a ring 8 carried by sleeve 3 and engaging the side edge of the abutment. By moving the sleeve 3, the caliper-gauge can be moved along the body 2 for the purpose of testing its diameter when the reciprocating grinding disc has moved away from the body and caliper-gauge.

The work contacting portions of the gauge are thus carried by the ring 8 and the latter is permitted a certain amount of radial free or floating movement relatively to the sleeve 3. In the present illustration the back end of the ring 8 is provided with a flange 9, engaging the front end of the sleeve 3 and confined loosely in position by means of a flanged sleeve 10, shown as having screw-threaded engagement with the sleeve 3, which sleeve is in turn held in position by a suitable lock nut 11, the distance between the outer edge of the flange 9 and inner

face of the sleeve 10 being such that the ring 8 will be free to move or float to a limited extent radially. The relative movement of the parts of the gauge permits adjustment to compensate for eccentricity or wear, and also a floating movement in case the work vibrates in relation to the spindle.

Furthermore, if desired, the movement of the caliper-gauge may be controlled by the feeding mechanism which moves the grinding disc across the body 2, so that the gauge is automatically moved towards or over the body 2 during the return movement of the grinding disc away from the body. Thus a cut-off or de-clutching device can be operatively connected with the gauge automatically to cut off or arrest the feed movement of the grinding disc, when the body 2 has attained the desired diameter, i. e. when the gauge can be moved past the body. The mechanism above referred to is illustrated in Figs. 2 and 3 where it will be seen that a swingable frame or slide 12, carrying the grinding disk 9, is connected to the sleeve 3 by means of links 13 and 14. The link 13, which is pivotally and slidably connected between its ends to the sleeve 3 by means of a pin 13^a shown by dotted lines in Figs. 2 and 3, engaging loosely in a peripheral groove 3^a in the sleeve 3, is at 30 end pivotally connected with a stationary a 15 secured on or forming part of the main frame of the machine. At its other end the link 13 is pivotally connected with one end of the link 14, and the other end of link 14 is pivotally connected to the slide 12. The link 14 is preferably made in two parts which slide endwise relatively to each other, and are connected and normally yieldingly restrained from extension movement by means of a spring 14^a. The spring and the expandible link 14 permit swinging movement of the slide 12 and of the grinding disk 9 over the roller 2, even though the caliper gage cannot pass over the roller.

Fig. 2 shows the relative positions of the parts, for instance for the commencement of the grinding operation. The slide 12 is assumed to be moving towards the right in Fig. 2 to carry the grinding disk 9 from the full line position to the dotted line position. At the same time the link 13 and the caliper gage will also be moved towards the dotted line position, and if the roller has not been ground down sufficiently to permit the caliper gage to pass thereon, further movement of the grinding disk 9 will be permitted by means of the expandible link 14 and the spring. When however, the roller has attained the desired diameter, the caliper gage will be permitted to pass over it to the position shown in Fig. 3. In this

position contact pieces 16 and 17 will be engaged with each other so as to close an electric circuit including an electromagnet 18. The electromagnet is shown as operating on a pawl 19 to withdraw it when the magnet is energized, from a ratchet wheel 20 constituting an element of the main drive 70 of the driving disk feed mechanism. Disengagement of the pawl 19 from the ratchet wheel cuts off or declutches the main drive from the driving apparatus and the driving operation is thereby arrested. 75

It will be obvious that the mechanism described in connection with Figs. 2 and 3 may be modified in many ways, since this mechanism is merely shown as constituting one means of effecting the requisite movements 80 of the caliper gage and the cut-off or disconnection of the main drive from the grinding machine when the work has been ground to required dimension.

I claim:

1. Means for testing the progress of grinding operations in grinding machines having a rotary spindle to carry the body to be ground, said means comprising a gage, and means for mounting said gage 90 relatively to the spindle to rotate with the body to be ground, said gage being movable into gaging relation to the body to be ground.

2. The combination with a rotary work 95 holding device, of a gage mounted relatively to the work holding device for rotation with the work and adapted to engage the work.

3. The combination with a rotary work 100 holding device, of a gauge adapted to engage the work carried thereby, and means for mounting the gauge on the work holder for rotation therewith, and reciprocation 105 axially thereof.

4. The combination with a rotary work carrying spindle, of a sleeve mounted to rotate therewith and reciprocate thereon, work engaging caliper members, and means for supporting the same upon said sleeve 110 and permitting movement thereof radially of the work-piece.

5. In combination with a work carrying spindle a ring provided with work engaging points adapted to engage the work, and means for mounting the ring on the spindle 115 to float radially thereof.

6. In combination with a rotary work holding device, a gage and means for mounting said gage in relation to said device to rotate in the same direction thereof, said gage being movable into and out of gaging relation to the work to gage the same. 120

In testimony whereof I have signed my name.

HENNING TEODOR TORNBERG.
